UNITED STATES PATENT OFFICE.

MATTHEW S. TARKINGTON, OF GREENSBURG, INDIANA.

WHIP-SOCKET.

SPECIFICATION forming part of Letters Patent No. 352,667, dated November 16, 1886.

Application filed June 14, 1886. Serial No. 205,058. (No model.)

To all whom it may concern:

Be it known that I, MATTHEW S. TARKINGTON, a citizen of the United States, residing at Greensburg, in the county of Decatur and State 5 of Indiana, have invented certain new and useful Improvements in Whip Sockets, of which the following is a specification.

My invention relates to whip-sockets, such as are attached to vehicles to receive and hold 10 the whip when not needed; and the objects of my improvements are to provide a whip socket or holder which will firmly grasp and hold the whip, and prevent its being lost or stolen.

I attain these objects by the mechanism 15 illustrated in the accompanying drawings, in which —

Figure 1 is a side view of my improved whip-socket and lock; Fig. 2, a longitudinal vertical section through the same; Fig. 3, a horizontal cross-section on line $x-x$ on Figs. 1 and 20 2; Fig. 4, a vertical cross-section on line $z-z$ on Figs. 1, 2, and 3.

Similar letters refer to similar parts throughout the several views.

25 A is the whip-socket, the same consisting of the socket proper, A', and the mouth-piece or receiver A². The socket A' and the mouth-piece A² are provided, where they are attached to another, with outward-projecting flanges a' and a², respectively. These flanges a' and a² form a slotted chamber, B, for the forked end C of the lock-bar D to slide and operate in. This lock-bar D extends out from the slotted chamber B, passing through a combination 30 locking device, F, which is firmly secured to the socket A' and the mouth-piece A².

The office of the bar D is to hold a whip of any size firmly in the socket A. This object is accomplished by pushing the bar D into the 40 socket until the forked end C grasps the whip and presses the same against the opposite wall of the socket A.

In Fig. 3 the dotted lines show the bar D and the fork C in their extreme positions when 45 holding a whip of the smallest or largest size, respectively.

The locking device F is constructed and operates in the following manner: The casing F, through the center of which the lock-bar D 50 slides, has one or more revolving face plates or dials, M. Each of these dials M are pro-

vided on the back side with an annular projecting flange, m. The side of the lock-bar D toward these face-plates M is provided with vertical recesses or notches d d d, cut into the 55 side of the bar D at regular intervals. The above-mentioned projecting flanges m of the dials M engage or extend into these recesses d d, thus firmly holding the bar D in place and locking the whip in the socket A when the 60 said bar D, with its forked end C, is pushed into the socket and against the whip. In the annular flanges m openings o o are left opposite each other, so that when the dial M is turned around until these openings o o are on 65 a plane with the bar D the said bar D can pass and slide in or out.

By lettering or figuring the faces of the casing F and of the dials M, M a certain combination of figures or letters is obtained at which 70 the annular flanges of the dials will permit the bar D to be moved.

As soon as one of the dials is turned, thus breaking the combination, the bar D is locked in place, and only persons acquainted with the 75 combination are enabled to release the bar and unlock the whip.

In order to keep the mouth of the whip-socket unobstructed and ready to receive the whip, and in order to avoid the necessity of 80 pulling the bar D out of the socket whenever the same is unlocked to release the whip, I secure a spring, S, in the socket A, which spring, having the tendency to lay snugly against the wall of the socket and engaging into a slot or 85 opening cut in the forked end C of the bar D, will push the bar D outward whenever the same is unlocked.

To avoid the possibility of strangers finding out the combination—a fact which might occur 90 by the spring S suddenly throwing out the bar D in case the dials should accidentally be turned into the unlocking position—I place a pawl, L, in the lock-casing F, underneath the bar D. This pawl L engages into notches cut 95 in the under side of the bar D, and it is firmly held in place by a spring, l, thus restraining the bar D from outward motion.

To disengage the pawl L and to release the bar D, so that the whip can be unlocked, it is 100 necessary to slightly move the lever-arm of the pawl.

Having thus fully described my invention, what I claim, and desire to secure by Letters Patent, is—

1. The combination, with the whip socket A, consisting of the socket proper, A', and the mouth-piece A², both being provided with the flanges a' and a², forming the slotted chamber B, of the forked lock-bar D, provided with the vertical notches d d, and operating as described, and the combination locking device F M m, all constructed as described, and for the purpose specified.

2. The combination, with the whip socket A, being formed by the socket proper, A', and the receiver A², as described, of the forked lock-bar D, provided with the vertical notches d d, the combination locking device F M m, constructed as described, and the spring S, engaging into and operating the lock-bar D, all arranged as described, and for the purpose specified.

3. The combination, with the whip-socket A, consisting of the socket proper, A', and the receiver A², having the flanges a' and a², and forming the chamber B, of the forked lock-bar D, provided with the vertical notches d d, the combination locking device F M m, the spring S, operating the bar D, when unlocked, and the pawl L, engaging into notches on the under side of the bar D, all substantially constructed and arranged as described, and for the purpose specified.

In testimony whereof I have signed my name to this specification in the presence of two subscribing witnesses.

MATTHEW S. TARKINGTON.
